UNITED STATES PATENT OFFICE.

VICTOR V. DIBOVSKY, OF KINGSWAY, LONDON, ENGLAND.

MACHINE-GUN.

1,298,913.

Specification of Letters Patent.

Patented Apr. 1, 1919.

Application filed April 10, 1918. Serial No. 227,777.

To all whom it may concern:

Be it known that I, VICTOR VLADIMIROVITCH DIBOVSKY, a Russian subject, captain of the Russian naval general staff, and whose 5 post-office address is Canada House, Kingsway, London England, have invented certain new and useful Improvements in Machine-Guns, of which the following is a specification.

10 This invention relates to machine-guns. The rate of fire of an automatic gun can be increased by increasing the rate of reciprocation of the breech-block and other parts coöperating therewith. If the said 15 rate of reciprocation is increased, disadvantages arise because the liability of the mechanism to jam is increased. It is to a device in the extractor-mechanism of a high-speed machine-gun, to counteract this 20 disadvantage, that the present invention relates.

In a gun provided with an extractor moving with the lock-casing and upheld by guides during the first portion of the rearward movement of the lock, and having to 25 pass clear from those guides and descend across the face of the lock-casing during an interval in which the lock completes its rearward movement and commences its 30 turn movement, there is a possibility, when the gun is firing rapidly, that if the descent of the extractor be left to the action of gravity alone it will not descend fast enough to prevent it from being caught against the 35 guide-ends in the return movement of the lock. Accordingly the present inventor having found the extractor-controlling devices in existing weapons inefficient has devised an improved device as follows:—He 40 provides a spring always in compression (or tension) resting at one end against a portion of the lock or its casing and at the other end against a projection from the extractor in order to accelerate the descent 45 of the extractor. By this means the rate of descent of the extractor with the cartridge carried by it is increased, and the extractor will be no longer liable to be caught by the returning lock and jammed against the 50 guide-ends; moreover the spring will cushion or buffer the extractor on the upstroke of the latter.

This invention therefore comprises, in a gun provided with an extractor moving with the lock-casing and upheld by guides from which it passes clear when it is neces-

sary that it should descend toward the cartridge-belt, the combination with that extractor of a spring that is always in compression (or tension), is carried on the lock-casing and is adapted to accelerate the descent of the extractor and to cushion the upstroke of the extractor. In a preferred construction according to this invention, the extractor is formed or fitted with a projection passing through a slot in the front wall of the lock-casing and downwardly acted on by a spring in compression, situated inside the lock-casing.

The invention is hereinafter described in 70 its application to a Vickers gun of a type already well-known and firing small-arm ammunition.

The accompanying drawing is an elevation, partly in section, of the rear end of the 75 casing of a gun showing one construction of the improved guiding device by which the descent of the extractor during its rearward motion with the lock is insured.

Referring to the drawing, EX is an extractor arranged to slide vertically up and down on the forward face of the lock-casing LC, and G is one of two stationary guides or cams attached to the cheek-plates of the gun-casing at each side of the lock. 80 Projections *ex* extend from each side of the extractor and ride upon the top of the guides G during the rearward movement of the lock-casing until they pass the rear end of the guide G. In order to insure that the 85 extractor shall descend smartly when it is clear of the guide G, a projection EX¹ is provided on the rear side of the extractor extending through a slot SL in the lock and having a pin EP upon it around which is 90 coiled the lower end of a helical spring ES always in compression between the projection EX¹ and a portion of the interior of the lock-casing above it. The spring ES when 95 the extractor rises, will "buffer" it so as 100 to reduce the violence of the shock with which the upstroke of the extractor will be checked.

Though the spring ES is shown and described as a helical spring in compression, other forms of spring might be used instead. For instance a helical spring in tension might be placed under the projection EX¹ and arranged to pull it downward, or other suitable forms might be used instead of helical springs, this invention comprising the 105 employment of a spring carried by and trav-

eling with the lock-casing LC, always ready to act for the purpose of promptly carrying down the extractor EX during the recoil movement thereof as soon as it has cleared 5 the rear ends of the guides G, and of checking the extractor during the upward movement thereof.

What I claim as my invention and desire to secure by Letters Patent is:—

10 1. In a machine gun, the combination with a lock casing, an extractor carried thereby, and means for guiding said extractor in the direction of the length of the gun, said extractor being movable relative 15 to the casing when disengaged from the guiding means, of a spring carried by the lock casing and coöperating with the extractor to accelerate movement thereof relative to the casing when disengaged from 20 said guiding means.

2. In a machine gun, the combination with a lock casing, an extractor carried thereby, and means for guiding said extractor in the direction of the length of the gun, the extractor being movable transversely of the gun when disengaged from 25 the guiding means, of a spring coöperating with the extractor to accelerate movement thereof relative to the casing in one direc-

tion and decelerate its movement in the opposite direction.

3. In a machine gun, the combination with a lock casing adapted to reciprocate in the direction of the length of the gun, an extractor mounted on the front of said 35 casing and means for guiding the extractor during reciprocations of the casing, the extractor being movable transversely of the gun when it is disengaged from said guiding means, of a spring arranged within the casing and adapted to accelerate such transverse movement of the extractor.

4. In a machine gun, the combination with a lock casing adapted to reciprocate in the direction of the length of the gun, an 40 extractor carried by the casing, and means for guiding the extractor during such reciprocation of the casing, the extractor being movable transversely of the gun when disengaged from said guiding means, of a projection 45 on the extractor extending through a slot in the casing, and a spring arranged within the casing and coöperating with said projection on the extractor to accelerate transverse movement thereof.

In testimony whereof I affix my signature.

V. V. DIBOVSKY.
